UNITED STATES PATENT OFFICE.

EUGENE B. WALSH, OF BROOKLYN, NEW YORK, ASSIGNOR, BY DIRECT AND MESNE ASSIGNMENTS, TO THE WALSH MANUFACTURING AND HEATING COMPANY, INC., A CORPORATION OF NEW YORK.

THERMOSTATIC PRESSURE-VALVE.

1,232,130.

Specification of Letters Patent.

Patented July 3, 1917.

Application filed January 5, 1915, Serial No. 590. Renewed March 21, 1917. Serial No. 156,457.

To all whom it may concern:

Be it known that I, EUGENE B. WALSH, a citizen of the United States, and a resident of the borough of Brooklyn, city and State of New York, have invented certain new and useful Improvements in Thermostatic Pressure-Valves, of which the following is a specification.

This invention has special reference to a new and useful thermostatic or pressure valve adapted for particular use in connection with a radiator heater, although the valve may be used with other heating systems or storage devices wherein it is desired to automatically cut off a supply of fluid and in the present instance to cut off the supply of fuel to a burner for the heater.

Another object of the invention is to provide a compact and thoroughly reliable automatically operating valve which is particularly adapted for operation under increasing pressure due to the increase in the temperature in the radiator, so that the supply of gas or other fuel to the burner of a radiator heater may be automatically regulated to maintain the water at a uniform temperature and to maintain a uniform generation of steam, while means are also provided for facilitating the supplying of the radiator with water and for determining the height of the water therein.

In the drawings forming part of this application:

Figure 1 is an end view of the lower end 35 of a radiator having a heater and my improved valve attached, in which view parts are broken away to more fully illustrate the construction,

Fig. 2 is a sectional view, taken on the line 2—2 of Fig. 1 and

Fig. 3 is a sectional view, taken on the line 3—3 of Fig. 1,

In the illustrated embodiment of my invention 1 indicates a radiator of ordinary construction, only a portion of which is shown because the remainder is well known. It comprises the sections 2 adapted to contain water and they communicate through common connecting pipes 3 in the bosses 4, 50 through which water and steam may circulate. The radiator may be connected with a steam system or it may be an independent unit, since the present invention is not limited to either arrangement. In the use of

the device the lower portion of the radiator 55 is inclosed by a casing 5 having portions 6 fitting between the sections 2 so as to prevent the escape of the heat generated beneath the radiator before the desired effect has been obtained, and to thereby secure a 60 maximum heating of the water in the radiator.

The specific construction of this casing or heater forms the subject matter of a co-pending application filed concurrently herewith 65 and serially numbered 591. The casing partly consists of an angular piece 7 having integral or attached feet 8 by which the casing is supported in spaced relation to the floor. A bottom 9 is supported on the angular piece 7 and the legs 10 of the radiator fit within the casing and rest on the tops of the feet 8, whereby the radiator is supported upon the feet of the heater. There is another bottom plate, 11, supported on the first 70 one by the flanges 12, and separated therefrom to form a draft space 13. The plate 9 is open at 14 to admit air to the combustion chamber 15. In the combustion chamber there is arranged a burner consisting of 80 a tube 16 having apertures 17 to permit the fuel to escape and combustion takes place near these apertures. This burner is arranged inside the combustion chamber, between the radiator legs and under the sections 2 and it is adapted to heat the water in 85 the radiator.

The present device connects with the threaded boss 4 of the end section 2, so as to be automatically actuated by the increased pressure caused by the expansion of the water or steam in the radiator, or vice versa, and it comprises a relatively flat valve casing 18 formed of a section 19 having a threaded attaching extension 20 extending laterally therefrom for attachment to the boss 4 whereby communication is established between the interior of the radiator and the interior of the valve casing 18.

The other section 21 of the valve casing and the first mentioned section are both provided with apertured flanges 22, 23 removably connected by the screws 24, and a flexible diaphragm 25 is mounted between 105 the sections and held around its edge between the flanges 22, 23 whereby the diaphragm may be readily renewed when nec-

essary. Carried by the section 21 of the valve casing and preferably formed integral therewith is an auxiliary valve casing 26 which is connected with an inlet or supply pipe 27 which conducts the supply of fuel, such as gas, thereto, the communication being through a port 28 in the auxiliary valve casing.

The supply of fuel is regulated by means 10 of a valve 29.

It may be explained that any kind of fuel other than gas, such as kerosene, gasoline, may be used for fuel. After passing into the casing 26 the fuel passes out through a 15 port 30 and a pipe 31, which leads to a Bunsen tube 32 and mixing chamber 33. The latter is preferably supported in horizontal alinement with the burner 16 and it is connected with the latter. A needle valve 34 20 is provided to control the supply of fuel passing from the pipe 31 into the mixing chamber 33 and the burner. The valve 34 is removably attached to the end of the pipe 31 so as to permit the parts to be assembled and 25 disassembled conveniently. The valve casting 35 has a plate 36 which fits into the end of the Bunsen tube 32 and it is provided with a number of apertures 37 to allow air to enter the bunsen with the gas. In order 30 to admit an additional and regulated supply of air when desired I have provided a shutter 38 which fits over the end of the bunsen 32 and it has an opening 39 which is made to register more or less with the opening 40 in 35 the bunsen when the shutter is turned around. Thus the additional air supply may be regulated to suit the requirements.

In order to control the quantity of fuel or 40 gas supplied to the burner when the valves 29 and 34 are properly regulated a cylindrical valve 41 is provided, having a reduced end 43. This valve moves in a bore 42 in the casing 21, 26 at right angles to the bores 28 and 30 and it is removably connected to the 45 diaphragm by means of a fastening screw 44. This screw passes through the diaphragm and into the valve and on one side of the diaphragm there is a washer 45 and on the other a spring 46, all held together 50 by the screw. The spring 46 carried by the diaphragm has its free ends arranged to contact with the inner face of the casing section 21, so as to normally open the valve 41 and cause the diaphragm to assume the flat position shown in Fig. 2 when relieved of excessive pressure.

The valve casing has leading from its section 19 upper and lower horizontal extensions 47, 48 on the free ends of which are 60 angular members 49, and threaded on these latter are nuts 50 which hold a gage glass 51 which indicates the height of the water in the radiator to which the heater is attached. Water may be introduced into the radiator 65 through the valve casing 19 by removing the

screw plug 52 and pouring it through the plug opening.

When the device is first placed in operation the necessary water is introduced into the opening at the plug 52 and the diaphragm is straight or in a flat plane. The valves 29 and 34 are adjusted to permit the fuel to pass to the burner. The gas being ignited at the burner, heat is generated in the chamber 15 and it heats the water in the radiator to a point where steam is generated and circulated through the sections 2. When the pressure of the expanded water or steam has increased to the desired limit the diaphragm will be flexed by the pressure on one side thereof and against the action of the spring 46. Should the pressure become excessive and make necessary a decrease in the fuel supply the diaphragm will be flexed outwardly and this will move the valve 41 outwardly and decrease the opening at the ports 28, 30, and thereby decrease the flow of gas to the burner; but, owing to the slanting end of the valve 41 the supply will not be entirely shut off, but the flame will be reduced sufficiently to prevent excessive and dangerous heating of the water in the radiator. The diaphragm will vary between the extreme positions from time to time and thus will vary the supply of fuel, and control the generation of steam so as to preserve uniform temperature in the rooms.

Having described my invention, what I claim is:

1. In a pressure valve, the combination 100 with a reservoir adapted to contain water under pressure and having a water supply connection and a threaded opening near its lower portion; of a diaphragm casing comprising two sections secured together, a diaphragm held between said sections and disposed normally rectilinear, one section having a reduced threaded extension for engagement with the threaded portion of the reservoir, the other section of the diaphragm 105 casing having an angular fitting integral therewith and provided with a valve seat, a valve connected to the diaphragm at the central portion thereof and operating through said diaphragm section to coöperate with the valve seat and regulate the size of the passage therethrough, a supply pipe connected with one end of said angular fitting, and a burner communicating with the other connection and receiving a supply of fuel therethrough for the heating of the water in the reservoir, variation in the internal pressure in the reservoir due to the heating of the water at various temperatures serving to close or open the valve by varying pressures on the diaphragm.

2. A thermostatic valve comprising a casing, a diaphragm in the casing, said casing having an opening with an extension adapted for attachment to a radiator, an auxiliary 130

valve integral with the casing and having a seat, a cylindrical valve connected to the diaphragm and operating through the casing to separate the interior of the diaphragm 5 from the auxiliary valve, a spring normally maintaining the diaphragm rectilinear and the valve unseated, said valve carried by the diaphragm loosely coöoperating with said seat to partly cut off the supply when seated, 10 a supply pipe for fuel communicating with the auxiliary valve, a burner to heat the water in the radiator, an outlet pipe also communicating with said auxiliary valve and

with the burner, said valve being shifted by the flexing of the diaphragm under excessive pressure to restrict the flow of fuel to the supply pipe, and a gage glass having a filling member for supplying water to the radiator.

Signed this 22nd day of December, 1914, 20
